UNITED STATES PATENT OFFICE.

EDWIN F. MORTON, OF PORTLAND, MAINE.

INDEX ATTACHMENT FOR TELEPHONE-DIRECTORIES.

No. 909,641.

Specification of Letters Patent.

Patented Jan. 12, 1909.

Application filed September 14, 1908. Serial No. 452,833.

To all whom it may concern:

Be it known that I, EDWIN F. MORTON, a citizen of the United States of America, and a resident of Portland, county of Cumberland, State of Maine, have invented certain new and useful Improvements in Index Attachments for Telephone-Directories, of which the following is a specification.

My invention relates to an index attachment 10 for telephone directories and other like books where the pages of the book are indexed by letter.

In the telephone directories as now commonly published there is often included in 15 one book a considerable number of different towns and cities and for the people of each town or city it is inconvenient to find the right place in the book each time the telephone is used or a number looked up.

20 The object of my invention is to provide an indexing attachment which may be easily and quickly applied to such telephone directories by which the section of the book devoted to the particular town or city may 25 be quickly found and the desired name located, the whole device being preferably made with covers embracing the directory and attachments and forming a temporary binding of ornamental appearance. These 30 objects are carried out by means of my present invention hereinafter shown and claimed.

I illustrate my invention by means of the accompanying drawing in which—

Figure 1 is a perspective view of a telephone directory fitted up with my indexing and binding attachment, Fig. 2 is a view of one of the indexing leaves and Fig. 3 is a section through the book.

In the drawing, *e*, *e* represent the leaves 40 of telephone directory which is bound with a paper cover.

In applying my attachment, I provide a series of leaves as *D*, each of which is preferably of about the same length as the ordinary 45 leaves of the book with an index letter *d'* projecting from the front edge in the usual manner of index leaves. The width of the leaf *D* is preferably somewhat narrower than the leaves of the book so that it 50 will lie between the book leaves without striking the rear of the book.

A perforated tab *d* is formed on each rear corner of the leaf *D* each of these tabs being located beyond the ends of the book 55 leaves and preferably offset from the end of the index leaf itself. The tab as here shown

is also offset to the rear of the rear edge of the leaf *D* so that when it is inserted between the leaves of the directory, the tabs will come approximately flush with the back 60 of the book and beyond the end thereof. Both the index letter projections and the tabs *d* are reinforced by cementing on a strip of cloth or other strong reinforcing material. The front edge of the leaf immediately below the index letter is cut away to form a recess *d*² to admit the finger more readily in turning over the leaves.

Enough of the leaves *D* are furnished to comprise the entire alphabet and I usually 70 provide an extra leaf as *D'* containing the name of the town or city to be indexed with a tab *d*² at the top for this purpose. On the leaf *D* there are printed lines for conveniently noting numbers commonly used and 75 spaces for advertising, this feature being one of the most important ones in the device in point of usefulness because the leaves are very conspicuous in a telephone directory. The leaf *D* is composed preferably of very 80 strong paper somewhat heavier than the ordinary leaves of the book.

The leaves *D* are inserted between the leaves of the directory in the space covered by the town or city to be indexed the letters 85 being opposite the appropriate pages in the book. If any page of the book includes more than one letter, the several letters are placed on the margin of the leaf *D*.

In making up my book, I preferably make 90 use of a pair of covers *a* the covers and the tabs being secured together by two bolts or rivets each of which passes through one of the rear corners of the cover and through the perforations of the tabs binding all the 95 parts together and forming a temporary binder. To make the binding more substantial and permanent I prefer to make use of two metal angle pieces *b* one of which fits over the rear edge of each cover, each having an opening in the end through which the bolt passes. The two vertical flanges of the angle pieces thus constitute the back of the book and the horizontal flanges serve to strengthen the whole structure. It will be 100 understood that there is a flexible joint in each corner at the point where it is confined by the angle piece.

The parts are fastened together as here shown by a tubular bolt *f* which extends 110 through the tab perforations but is too small to pass through the holes in the cover.

and the angle piece. A pair of round headed screws f engage screw threads in the ends of the tube and serve to hold the whole together.

5 An index and binder such as above described enables the subscriber to quickly turn to the number wanted, it provides a neat and ornamental binding for the telephone directory which is usually a soiled and untidy looking book; it may be shifted from one book to another as new books come out and it furnishes a valuable advertising medium.

I claim:—

- 15 1. The herein described index attachment for telephone directories and other like books consisting of a series of index leaves provided with index letters on the front edge thereof and adapted to be inserted between the leaves of the book, each index leaf having a perforated tab at each rear corner located beyond the end of the book leaves and means for fastening said tabs together.
- 20 2. The herein described index attachment for telephone directories and other like books consisting of a series of index leaves provided with index letter tabs on the front edge thereof and adapted to be inserted between the leaves of the book, each index leaf having a tab at each rear corner located beyond the ends of the book leaves, and projecting in rear of the rear edge of said index leaf, and means for fastening said tabs together.
- 25 3. The herein described index attachment for telephone directories and other like books consisting of a series of index leaves provided with index letter tabs on the front edge thereof and adapted to be inserted between the leaves of the book, each index leaf having a tab at each rear corner located beyond the ends of the book leaves, and projecting in rear of the rear edge of said index leaf, and means for fastening said tabs together.
- 30 40 4. The herein described index attachment for telephone directories and other like books consisting of a series of index leaves provided with index letter tabs on the front edge thereof and adapted to be inserted between the leaves of the book, each index leaf having a perforated tab at each rear corner

located beyond the ends of the book leaves and projecting in rear of the rear edge of said index leaf, and a bolt or rivet passing through the perforations of said tab for fastening them together. 45

4. The herein described index attachment for telephone directories and other like books consisting of a series of index leaves provided with index letter tabs on the front edge thereof, and adapted to be inserted between the leaves of the book, each index leaf having a perforated tab at each rear corner located beyond the ends of book leaves and in rear of the rear edge of the index leaf, a pair of covers and a bolt or rivet passing through the rear corners of the covers and the perforations of said tabs to form a temporary binding. 55

5. The herein described index attachment for telephone directories and other like books consisting of a series of index leaves provided with index letter tabs on the front edge thereof, and adapted to be inserted between the leaves of the book, each index leaf having a perforated tab at each rear corner located beyond the ends of the book leaves and in rear of the rear edge of the index leaf, a pair of covers, a pair of metal angle pieces adapted to embrace the rear edges of said covers and a bolt or rivet passing through the ends of each angle piece, each rear corner of the covers and the perforations of the tabs to form a temporary binding. 75

In witness whereof I have hereunto set my hand this 19th day of August, 1908.

EDWIN F. MORTON.
